COMBINED GLARE SHIELD AND ARTICLE
HOLDER FOR VEHICLE SUN VISORS

Morris A. Sholl, 250 W. 15th St., Los Angeles, Calif.

Filed Dec. 1, 1958, Ser. No. 53,594

Term of patent 3½ years

(Cl. D14—6)

Fig. 1 is a front elevational view of a combined glare shield and article holder for vehicle sun visors embodying my new design, with the glare shield in inward position.

Fig. 2 is a rear elevational view of the same.

Fig. 3 is a front elevational view of the same with the glare shield in outward position.

I claim:

The ornamental design for a combined glare shield and article holder for vehicle sun visors, substantially as shown.
